DESIGN FOR A CASING FOR SPEECH INPUT APPARATUS

John B. Van Dyke, Cedar Rapids, Iowa, assignor to Collins Radio Company, Cedar Rapids, Iowa, a corporation of Iowa

Application October 28, 1938, Serial No. 80,735

Term of patent 14 years

To all whom it may concern:

Be it known that I, John B. Van Dyke, a citizen of the United States, residing at Cedar Rapids, in the county of Linn and State of Iowa, have invented a new, original, and ornamental

Design for a Casing for Speech Input Apparatus, of which the following is a specification, reference being had to the accompanying drawing, forming part thereof, and in which the figure

is a front perspective view of a casing for a speech input apparatus. The right and left hand end portions are the same and include centrally projecting ornamental webs or flanges.

I claim:

The ornamental design for a casing for speech input apparatus, as shown and described.

JOHN B. VAN DYKE.
